UNITED STATES PATENT OFFICE.

FRANK S. CROWELL, OF TOLEDO, OHIO, ASSIGNOR TO THE EDWARD N. RIDDLE CO., OF TOLEDO, OHIO, A CORPORATION OF OHIO.

DESIGN FOR AN ELECTRIC WALL BRACKET.

Application filed April 20, 1922. Serial No. 1,850. Term of patent 3½ years.

To all whom it may concern:

Be it known that I, FRANK S. CROWELL, a citizen of the United States, residing at Toledo, in the county of Lucas and State of Ohio, have invented a certain new, original, and ornamental Design for an Electric Wall Bracket, of which the following is a specification, reference being had to the accompanying drawing, forming part hereof.

Fig. 1 is a perspective view of an electric wall bracket, showing my new design.

Fig. 2 shows a diagrammatic view of my design to particularly denote contour and arrangement of parts.

I claim:

The ornamental design for an electric wall bracket, as shown.

FRANK S. CROWELL.
